PILOT VALVE CONSTRUCTION

Fredrick E. Beebe, Willowick, Ohio

Application May 19, 1945, Serial No. 594,779

1 Claim. (Cl. 158—117.1)

1

The invention relates to a novel and improved valve construction and more particularly to a novel and improved arrangement of a pilot valve and a main valve in a gaseous or other fluid combustion system.

An object of the invention is to provide a novel, improved, and extremely simple and efficient structure wherein the main valve and pilot valve are associated in a unitary housing.

Further objects and advantages will be apparent from a study of the following specification, in conjunction with the accompanying drawings, in which

Fig. 1 is a side elevation of a valve construction embodying my invention;

Fig. 2 is a sectional view taken on the line 2—2 of Fig. 1;

Fig. 3 is a sectional view taken on the line 3—3 of Fig. 2;

Fig. 4 is a sectional view taken on the line 4—4 of Fig. 2;

Fig. 5 is a somewhat enlarged view, in side elevation, with parts broken away and in section, showing internal details of the pilot burner;

Fig. 6 is a sectional view taken on the line 6—6 of Fig. 5, and

Fig. 7 is a side elevational view from the position of the line 7—7 of Fig. 1.

The valve arrangement herein shown is of the so-called safety pilot type wherein fuel gas flows from the supply source to the main burner in the combustion chamber only when the pilot flame is burning, and wherein the gas flow both to the main burner and to the pilot burner is cut off if for any reason the pilot flame is accidentally or intentionally extinguished. To accomplish this purpose a thermostatic device is disposed adjacent to the pilot burner, and is responsive to ignition thereof, so as to cause opening of the valve permitting flow to the main burner only when the temperature of the thermostatic element exceeds the critical operating point. This mode of operation is conventional, but the present structure whereby the operation is effected is distinctly novel and materially improved.

Referring now to the drawings, illustrating an embodiment of the invention, there is shown a chambered valve housing 11 having an inlet port 12 in communication with the gas supply (not shown), an outlet port 13 in communication with the main burner (not shown), and a pilot burner 14 associated with a bi-metallic thermostatic element 15. Progressive change in temperature of element 15 past a thermal critical point produces

2

appropriate opening or closing of valves in the housing interior, as will now be described.

The housing comprises a hollow body portion 17 provided with a central partition wall 18 which defines within the body a pair of generally similar chambers here termed, for identification, an upper or inlet chamber 19 in communication with the inlet port 12, and a lower or outlet chamber 20 in communication with the outlet port 13. An aperture 23 in wall 18 permits gas flow from chamber 19 to chamber 20 under the control of a pair of valves A and B arranged in series. In the embodiment here shown the valves seat by peripheral contact of resilient facing disks 24 with the respective upper and lower edge portions of aperture 23. Obviously both valves must be unseated to permit gas flow to outlet port 13 and thence to the main burner. The manner of operation of the valves will be described hereinafter.

The upper wall of chamber 19 is closed by a flexible metallic diaphragm 26 which is imperforate except for an aperture at its center which permits passage therethrough of the stem 27 of valve A. A gas tight seal is secured by the co-operating packing nuts 28 and 29. Diaphragm 26 is retained by a screw cap 30 which is centrally perforated at 31 to allow free movement of a plunger 32 in which the valve stem 27 is adjustably retained. It will be apparent that in assembling the apparatus, the normal unflexed position of diaphragm 26 compels a positive seating of valve A on wall 18. The seat is leakproof, but the valve is readily "cracked" by slight outward tension on plunger 32. Plunger 32 carries a manipulating nut 33 circumferentially slotted at 34. The slot 34 is straddled by the bifurcated fingers 35 of thermostatic element 15, expansion of which effects outward movement of plunger 32 to produce unseating of valve A. The plunger may also be manipulated manually to produce the same effect.

Elements in and adjacent to the outlet chamber 20 which are similar to those just described in the last preceding paragraph are identified by similar reference numerals with the suffix "b" appended thereto.

The novel arrangement of the pilot burner supply passage will now be described.

The partition wall 18 is provided with a drilled passage 40 extending from central aperture 23 outwardly to, and communicating with, the pilot burner 14. As long as valve A is open, even a slight amount, gas from inlet chamber 19 flows to aperture 23 and thence through passage 40 to

an extension thereof 40a in the pilot burner, regardless of whether valve B is open or shut.

As heretofore indicated, when the system is not in operation and the thermostatic element is at room temperature or not materially above room temperature, both valves A and B are normally closed. However when the system is in operation, and the pilot is burning, thermostatic elements 15 increase in temperature and rapidly reach a critical point where they urge their respective elements outwardly so as to open valves A and B. To start operation from a cold system however, valve A must be manually unseated by lifting nut 33 to permit gas to flow to the pilot. The pilot is then ignited while holding valve A open. The tongues 15a affixed one to each leg of element 15, are directly subjected to the pilot flame, and cause said legs to quickly heat up. One such leg maintains valve A open, and the other opens valve B to the main burner which is thereupon ignited by the pilot flame.

I have provided automatically releasable abutment means which may be used to maintain nut 33 in raised position until the heat of the pilot flame takes effect, as described immediately above, after which said abutment drops out of operative engagement with nut 33. Said abutment (Fig. 7) consists of a lever 38 freely movable on a pivot pin 39 affixed to cap 30 on the valve body, and normally biased to drop by gravity to the full line position. When starting the burner and pilot devices from a cold condition, the nut 33 is lifted, and the free end of lever 38 is swung up and inserted thereunder in the dotted line position, where it is retained by the nut under the influence of the inward bias of thermal element 15. When the pilot is lighted, and the thermal element 15 heats sufficiently to reverse said bias and tends to move the nut 33 outwardly, the lever 38 drops again to the full line position, and operation proceeds as previously described.

Gas flow between outlet port 13 and the main burner may be normally subjected to further control, for example by a room thermostat (not shown) which intermittently stops or starts flow of fuel to the main burner. The pilot burner insures flow of fuel through the main valves herein shown and described, and through said valves to the other valve (not shown) controlled by the room thermostat.

Should the pilot valve for any reason be accidentally or unintentionally extinguished, element 15 will cool and both the valves A and B will

almost immediately close, thereby rendering the system safe and fool proof until it is again started manually, as already described.

Figs. 5 and 6 illustrate in somewhat greater detail the structure of the pilot valve which is fed through a passage 40 constituting a continuation of the passage 40 in partition wall 13. A nipple 50, integral with the valve body, has a hexagonal external contour in cross-section, and an inner sleeve 51 has a pressed fit thereon. An outer sleeve 52, coaxial with the inner sleeve and the nipple, has a threaded connection on the shoulder 53 at the base of the nipple. The outer sleeve has therein a circumferentially spaced series of perforations 54. The device operates as follows. When gas flows upwardly (Fig. 5) through passage 40a a flow of primary air is inspired through apertures 54, and upwardly through the segmental clearance channels 55 (Fig. 6) between nipple 50 and sleeve 51. A secondary air current flows upwardly through the annular passage 56 between sleeves 51 and 52. The volume of gas is controlled by an adjusting screw 57 (Fig. 1) in the valve housing. An efficient gas-air mixture, and an adequate secondary air supply is assured by the structure just described.

What I claim is:

Structure of the character described comprising a hollow valve housing, a partition disposed transversely within said housing whereby to divide said housing into two chambers, an inlet port in one chamber for communicating with a gas supply source, an outlet port in the other chamber for communicating with main burner means, said partition being provided with an aperture therethrough to permit gas flow from one chamber to the other, said partition being further provided with a passageway extending laterally within said partition from said aperture to the exterior of said housing, a pilot burner communicating with the outer extremity of said passageway, a pair of valves in said housing disposed in the path of gas flow, one valve of said pair on the inlet side of said aperture and the other valve of said pair on the outlet side of said aperture whereby opening of the valve on said inlet side feeds said pilot burner and opening of both said valves feeds said main burner, and thermostat means responsive to the flame of said pilot burner, and operatively associated with said pair of valves, for controlling the operation thereof.

FREDRICK E. BEEBE.
